UNITED STATES PATENT OFFICE.

EDWIN C. WASHBURN, OF ENGLEWOOD, NEW JERSEY, ASSIGNOR OF ONE-THIRD TO
ROBERT S. BLAIR, OF SOUTH ORANGE, NEW JERSEY.

APPARATUS AND ART FOR HANDLING COAL AND THE LIKE.

1,347,000.

Specification of Letters Patent. Patented July 20, 1920.

Application filed July 18, 1918. Serial No. 245,577.

To all whom it may concern:

Be it known that I, EDWIN C. WASHBURN, a citizen of the United States, and a resident of Englewood, in the county of Bergen 5 and State of New Jersey, have invented an Improvement in Apparatus and Art for Handling Coal and the like, of which the following is a specification.

This invention relates to the handling 10 and more particularly to the thawing of coal and the like. One of the objects thereof is to provide simple and efficient means for the handling of coal, and particularly coal in frozen condition. Another object is to 15 provide apparatus of the above type which shall be rapid in action and economical of heat. Another object is to provide a practical and convenient art for handling frozen coal and the like. Other objects will be 20 in part obvious and in part pointed out hereinafter.

The invention accordingly consists in the features of construction, combinations of elements, arrangement of parts and in the several steps and relation and order of certain 25 of the same, all as exemplified in the apparatus and art hereinafter described and the scope of the application of which will be indicated in the following claims.

30 In the accompanying drawing, in which is shown one of various possible embodiments of the mechanical features of this invention,—

Figure 1 is a diagrammatic plan; 35 Fig. 2 is a diagrammatic elevation on a similar scale;

Fig. 3 is a side view of a portion of the parts shown in Fig. 1, the scale being larger and certain of the parts being broken away;

40 Fig. 4 is an enlarged cross-section along the line 4—4 of Fig. 1; and

Fig. 5 is a similar view along the line 5—5 of Fig. 1.

Similar reference characters refer to similar 45 parts throughout the several views of the drawing.

Referring now to Fig. 2 of the drawings, there is shown a railway track which may at the initial or what may be termed "ingoing" position 10, be substantially at the 50 level of the ground 11. At this point it enters a tunnel which is continued throughout the length of the apparatus.

From the point 10 the tunnel inclines 55 downwardly as at 12 and thence upwardly as at 13 to the central portion 14. Continu-

ing in the same direction the tunnel again inclines downwardly at 15 and thence upwardly at 16 from which point it may return above the level of the ground. The 60 exit end is preferably materially lower than the entrance end, and it will thus be seen that upon cars being moved through, coupled in trains, no power will be required to move them at the desired slow rate. The 65 depressions 17 and 18 mark the limits of a relatively elevated chamber of such nature that heated air therein will remain in position and not tend to travel by convection to the outer atmosphere. For this purpose 70 in so far as the broader aspects of certain features of this invention are concerned, it is necessary only that there be provided a chamber to which access may be had by track and from which, due to its upwardly 75 inclined approach, the heated air will not tend to pass. Accordingly the term "tunnel" is used in a broad sense to cover any equivalent structure.

The above track, 19, may be branched 80 within the central chamber to provide one or more side tracks 20 with greater accommodation of cars.

The entire track is preferably housed by walls of low heat conductivity, the construction of which will later be described in detail.

Positioned at any suitable point but preferably beneath the portion 14 of the tunnel, 90 are one or more suitable sources of heat 21 here shown as steam boilers. The track at this point is open to permit the heat from the boiler room 22 to pass directly into the chamber above. Also the steam from the boilers is led through pipes which may lie 95 longitudinally between the rails along the tracks as indicated at 23 in Figs. 4 and 5 of the drawing.

At the central portion, the walls mounted on suitable piers 24 comprise an outer portion 25 and inner portions 26 both formed of reinforced concrete or like material. The space 27 between the walls may be connected to the up-takes 28 from the furnaces and discharge through stacks 29 at the roof of the 105 tunnel.

The single track portion of the tunnel shown in section at Fig. 5 comprises the inner and outer walls 30 and 31 having air space therebetween.

If desired, at suitable points in the walls, 110 windows 32 may be provided preferably of

the double sash type to economize heat, it being understood that the frames of these windows extend entirely through the spaces 27 to exclude the furnace gases from the glass.

In the use of the above apparatus, the cars containing coal or the like, the contents of which are in frozen condition, are drawn or pushed into the tunnel as at 10 and they 10 may travel at a slow rate throughout the length of the tunnel, or, if desired, may be intermittently stopped in order to permit more thorough thawing of their contents. The grades being balanced or their total ef- 15 feit being downward, a continuous train of cars may be moved through the tunnel with little or no effort. When the cars emerge from the tunnel as at 33 they are preferably immediately run over coal pockets and the 20 contents dumped, although if desired they may be dumped before they emerge from the tunnel by the provision of suitable pockets beneath the track. Any cars requiring an extra thawing treatment may be side- 25 tracked on the branch track 20 and left as long as is necessary to bring about the desired result.

In the action of the above apparatus it will be seen that no expensive structure is 30 required and that the use of the heat is extremely economical. The heated air in which the cars are thawed is not withdrawn by the passage of cars therethrough and the only heat utilized is that actually employed 35 in thawing coal. Furthermore, this is accomplished without the use of gates, thus simplifying and cheapening the apparatus and avoiding loss on the opening of such parts. Also any heated air which may es- 40 cape is compelled by the tunnel to travel along the cars, thus warming them up prior to thawing or aiding in keeping them in properly thawed condition. The heat devel- 45 oped in the boilers is utilized not only by the steam action but even that which would ordinarily escape through the up-take or from radiation, is used. Also the shape of the tunnel walls avoids square corners and pockets, thus holding the heated air closely 50 about the cars and their loads. It is to be understood of course that it is not necessary however, to use all of these various sources of heat.

It is to be especially noted moreover, that 55 the above art may be rapidly carried on, the motive power as well as heat being economically employed. The method moreover, as hereinbefore noted, is preferably carried on continuously, the cars being con- 60 nected in long trains or, if desired, added car by car to the moving train within the tunnel as cars are removed from the exit end.

It will thus be seen that there is provided 65 apparatus and an art in which the several

objects of this invention are achieved and that the same are well adapted to meet the hardest requirements of practical use.

As the mechanical features of this invention might be embodied in apparatus which 70 would be apparently radically different and as the art might be carried on by means of different apparatus, it is to be understood that all features herein described or shown in the accompanying drawing are to be interpreted as illustrative and not in a limiting sense. 75

I claim as my invention:

1. In thawing apparatus for coal and the like, in combination, a track portion, means 80 inclosing the space about said track portion and adapted to retain heated air therein by its buoyancy, means adapted to heat said space, and a track portion inclined downwardly under said inclosing means and thence inclined upwardly to join said first track portion.

2. In thawing apparatus for coal and the like, in combination, a track having an upper portion and downwardly inclined por- 90 tions leading to and from the same, air-retaining means inclosing said track substantially down to the level of its upper portion and retaining the heated air therein by its buoyancy, and means adapted to heat the space so inclosed.

3. In thawing apparatus for coal and the like, in combination, a track section adapted to support a railway car, air-retaining means inclosing said track section substan- 100 tially down to the level of the track, means adapted to heat the space thus inclosed, and means adapted to lead a car upwardly into and downwardly out of said space, said space being free from connections tending 105 to force fluid thereinto or draw fluid therefrom.

4. In thawing apparatus for coal and the like, in combination, a track having a relatively raised portion and an inclined por- 110 tion and provided with a branch track at said upper portion, means extending downwardly over said inclined portion adapted to inclose the raised portion of said track and retain heated air by its buoyancy in the 115 space about the upper portion thereof, and means adapted to heat the space thus inclosed.

5. In thawing apparatus for coal and the like, in combination, a track having an up- 120 wardly inclined portion and a raised portion to which said first portion extends, a double-walled inclosure for the raised portion of said track extending downwardly over said inclined portion and adapted to retain heated air by its buoyancy in the 125 space about the raised portion thereof, and means adapted to heat the space within said inclosure.

6. The art of conditioning coal for han- 130

- dling, which consists in heating air confined by its buoyancy within a tunnel inclined downwardly toward each of its open ends and having tracks extending along the same, 5 and moving railway cars laden with coal in frozen condition along the tracks through the confined air and retaining them therein until thawed.
7. The art of conditioning coal for han-
10 dling, which consists in heating air confined by its buoyancy within a tunnel inclined downwardly toward an open end and having tracks extending along the same, and moving railway cars laden with coal in frozen condition along the tracks through 15 the confined air and retaining them therein until thawed.
8. The art of conditioning coal for han-
10 dling, which consists in heating air confined by its buoyancy within a tunnel inclined downwardly and thence upwardly toward an open end and having tracks extending along the same, and moving railway cars laden with coal in frozen condition 25 along the tracks downwardly and thence upwardly into said confined air and retaining them therein until thawed.
9. In thawing apparatus for coal and the like, in combination, a track section adapted 30 to support a railway car, air-retaining means inclosing said section substantially down to the level of the track, heat-generating means positioned below the space thus inclosed, means adapted to lead heat into 35 said space from said heat-generating means, and means adapted to lead a car under said air-retaining means first upwardly into and thereafter downwardly out of said space.
10. In thawing apparatus for coal and the 40 like, in combination, a track section adapted
- to support a railway car, air-retaining means of heat-insulating constitution inclosing said track section substantially down to the level of the track and retaining the heated air therein against escape in a downward direction by its buoyancy, means adapted to heat the space thus inclosed, and an upwardly inclined track leading under said air-retaining means and into said space. 45
11. In thawing apparatus for coal and the like, in combination, a track section adapted to support a railway car, a track section leading thereto in an upwardly inclined direction, a track section leading therefrom in a downwardly inclined direction, means of heat-insulating constitution inclosing said first track section substantially down to the level thereof and thereby extending over said second and third track sections, means adapted to heat the air with- 50 in said inclosing means, said heated air being confined substantially against escape by its buoyancy within said inclosing means, and a railway track leading to said first section and from said third section whereby 55 trains may be continuously run through said inclosed space. 60
12. In thawing apparatus for coal and the like, in combination, means forming a substantially tight chamber adapted to retain heated air, means adapted to heat said chamber, and means forming an upwardly directed passage inclosed at the top, bottom and sides and leading into said chamber and adapted to transmit railway cars thereinto. 75

In testimony whereof I have signed my name to this specification this 11th day of July, 1918.

EDWIN C. WASHBURN.
